Mrs. Schumacher ATTORNEY

UNITED STATES PATENT OFFICE

BENJAMIN GOLDMAN, OF NEW YORK, N. Y.

RAZOR

Application filed June 25, 1930. Serial No. 463,615.

This invention relates to razors and razor blades.

One object of the invention is to provide an improved razor for shaving with the edge portions of the blade lying substantially flat or nearly so against the surface being shaved.

Another object of the invention is the provision of a razor having improved means to curve the blade through a relatively large angle whereby the edge portions of the blade will have substantially solely a cutting action on the hair, eliminating any tearing or pulling of the hair, thus producing an even and uniform shave, and with the blade being reliably held along predetermined lines for an efficient cutting action.

Another object of the invention is to furnish an improved device of the type mentioned wherein the razor and blade co-operate through the curvature of the former and the resilience of the latter, so that the cutting edge portions of the blade may lie as nearly tangent as possible to the surface being shaved, with the said edge portions being nevertheless rigidly retained.

Another object of the invention is to provide a razor which can be made of sheet metal, as a stamping, or the like, and having stiffening elements, disposed, for example, to engage around the side edges of the lower guard member of the razor.

A further object of the invention is to provide a device of the character described having relatively few and simple parts, which device is inexpensive to manufacture and assemble, neat in appearance, durable in construction, and convenient, reliable, and efficient in use, and also a blade which is of improved construction and constructed to be easily flexed through a large angle, and which may be of such shape as to afford economy in the material consumed in constructing the blades.

Other objects and advantages of the invention will become apparent as the specification proceeds.

With the aforesaid objects in view, the invention consists in the novel combinations and arrangements of parts hereinafter described in their preferred embodiments,

pointed out in the subjoined claims, and illustrated on the annexed drawings, wherein like parts are designated by the same reference characters throughout the several views.

In the drawings:

Figure 1 is a view in side elevation of a device embodying the invention showing the same somewhat enlarged.

Fig. 2 is a view in front elevation thereof with part of the handle removed.

Fig. 3 is an enlarged vertical sectional view of the device taken on line 3—3 of Fig. 2.

Fig. 4 is a view in side elevation of the cover member of the razor, with parts removed to show the internal construction.

Fig. 5 is a bottom plan view of the cover member of the razor.

Fig. 6 is a plan view of a razor blade.

Fig. 7 is a vertical sectional view like that of Fig. 3 showing a modified form of the invention.

Fig. 8 is a plan view of the modified razor blade therefor.

The advantages of the invention as here outlined are best realized when all of its features and instrumentalities are combined in one and the same structure, but, useful devices may be produced embodying less than the whole.

It will be obvious to those skilled in the art to which this invention appertains, that the same may be incorporated in several different constructions. The accompanying drawing, therefore, is submitted merely as showing the preferred exemplification of the invention.

Generally described, the invention provides a large curvature razor having a seat and guard member to receive a double edged blade, and also a cover or holding member which sets over the blade, the several parts being removably held together by a conventional screw and handle construction. To afford a large curvature, the blade may be elongated between the cutting edges thereof in proportion to the angle of the curve. Preferably this angle is approximately 120 degrees, the blade being comparatively long in consequence, so that the curve is sufficient to avoid undue strain on the blade, and to

afford space for the central screw and handle structure. The length of a cutting edge of the blade may thus be seen to be less than the distance between opposite cutting edges. 5 To facilitate the flexing of the blade, the central part thereof may be made narrow, with its lines diverging toward the cutting edges. Also the central part may have one or more openings or slots to reduce the cross 10 section thereof. Since razor blades are made of a high grade steel, the desired flexure thereof can be readily accomplished. The razor may be constructed to cause most of the flexure of the blade to occur in the central part thereof. The curve of the blade has a stiffening effect upon the edge portions thereof, which renders feasible a razor constructed according to the principles herein defined. Utilization of the resilience 15 20 25 of the blade is effected with the cover bearing upon the razor at selected points adjacent to the cutting edges for stiffening the latter and to cause it to follow predetermined lines and with the cutting edges adapted to lie substantially flat against the surface being shaved. Thus a clean cutting action is obtained on the hair without a tearing or pulling thereon, producing a smooth shave. The cover member may be made of 30 sheet metal with downwardly bent marginal flanges to engage around the side edges of the lower or guard member of the razor. To interlock the razor parts any suitable means may be provided, one possible form of which 35 is illustrated herein.

Referring in detail to the drawings, 10 denotes a device embodying the invention. The same includes a razor for a novel double edged blade 11 more particularly described 40 hereinafter. The razor comprises a base member 12 having a seat 13 for the blade 11, a holding or cover member 14 for the blade above said seat, and handle 15. At the ends of the base member 12 are conventional 45 guards 16. Any suitable means are provided to removably interconnect the members 12 and 14, including a central screw 17 on the cover member, adapted to pass through a hole 18 in the base member, to be threaded into an axial bore 19 in said handle.

The blade 11 is stamped or otherwise formed of plane sheet steel, and provided with opposite cutting edges 20. Intermediate of these edges 20, the blade is considerably elongated, so that its length may be equal to, or preferably greater than the length of a cutting edge. This permits the blade to be flexed into any desired curve and 55 with any required angularity. To facilitate the flexing of the razor blade, the same is narrowed intermediate its ends to form a neck portion 21 toward which the opposite cutting edge portions taper along the side 60 edges 22.

To hold the blade in place in the razor, the cover member 14 has a short ridge 23 extending in opposite directions from the screw 17 lengthwise of the said member. The blade 11 is provided with a corresponding hole 24 and a slot 25, the former receiving the screw 17 and the latter the ridge. In the base member is a groove 26 to register with the ridge. 70

The opening 24 and slot 25 reduce the cross section of the neck portion 21 of the blade and facilitate the flexing thereof into the desired curve in the razor. These openings may be of any desired shape and size, and can be arranged as in Fig. 8 hereinafter described. 75

By the formation of cutouts in the sides 80 of the blade as shown at edges 22, a saving of material may be effected since a plurality of blades can be cut in staggered formation as shown by the dotted lines 27 in Fig. 6, 85 indicating a fragment of the blank of another razor blade.

To cause most of the flexure on the blade to occur at the central or neck portion thereof, the razor may be correspondingly formed, so that the seat 13 forms angles of approximately 60 degrees with the axis of the razor, as indicated by the handle 15. Thus the opposite seat portions form a total of 120 degrees. To afford a distribution of the stresses 90 on the blade, the seat has a central portion 28 lying substantially at right angles to the axis of the razor. This seat portion 28 is of sufficient length to provide space for the simplified ridge and screw construction. From the central seat portion 28 extend in 100 opposite directions seat portions 29 which may be substantially plane and slightly recessed at 30.

Both the base and cover members of the 105 razor may be made by molding, stamping, or the like, preferably the latter, for which purpose any suitable sheet metal can be used.

The construction of the cover member 14 as a stamping has an especial advantage since it can be inexpensively made and will have a 110 minimum thickness, permitting the blade to lie closely tangential to surface being shaved. Where a cheap material is used, the cover member may be stiffened by the provision of 115 ribs, flanges, or the like, and a particularly simple and compact construction is effected by forming marginal re-enforcement elements such as flanges 31. Thus there may be a flange on each side of the cover member to extend downward and in engagement with the opposite side edges of the base member. These flanges may each be integral with the cover member and continuous therewith in 120 length. In assembling the razor, the base 125 member may be easily set into the cover member between said flanges, the latter may perform the additional function of holding the said members against any lateral relative side movement. 130

At the ends of the holding member, the same may be formed with lips 32 to bear on the blade adjacent to the cutting edges thereof, and the blade may follow a curve in the 5 razor, whereby it contacts the cover member at 33 to predetermine the shape of the curve and to stiffen the blade.

With the cover member being made of very thin metal as stated, and the outer surfaces 10 34 thereof plane, the latter may serve as guides for the operator in holding the razor in substantially tangential shaving position.

The ridge 23 may be made as part of the cover member 14 or as a separate part to be 15 affixed thereto in a suitable manner. Thus the ridge may constitute an integral portion of a plate 35 extending crosswise of the cover member at the central part thereof and from flange to flange thereof. To secure the plate 20 to the cover member, the former may have projections 36 to be press fitted or headed over in corresponding openings 37 in the cover member. The screw 17 may afford additional holding engagement by having a 25 shoulder coaction at 38 with the plate.

In the construction of the razor, the resiliency of the blade is available as a stiffening factor to render the cutting edges of the blade 30 stiff for a proper cutting action, and such cutting action will be almost precisely transverse to the hairs to avoid tearing or pulling thereon, and afford a smooth shave.

It will be appreciated that there is an important relation between the length of the 35 blade and the curvature of the razor. This may be determined according to the relation of the length of an arc to the circumference, according to geometry. However, arcs of 40 varying angularity may be employed, although they ought in every case to be sufficient for the reception of the handle therebetween, since the razor must be light and compact. Furthermore, the degree of curvature to which the blade may be subjected must 45 be considered, including the quality of the steel and the construction of the blade.

In Figs. 7 and 8 is shown a modified form 50 of the invention, in which the construction may be substantially as hereinbefore described, but the blade 39 has a transversely extending slot 40 in the central part thereof to mate with a corresponding ridge 41 in the cover member. This slot 40 assures an easy 55 flexing of the blade. The plate 42 may be secured to the cover member as hereinbefore noted, or solely by the screw element of the razor.

It will be appreciated that various changes 60 and modifications may be made in the device as shown in the drawings, and that the same is submitted in an illustrative and not in a limiting sense, the scope of the invention being defined in the following claims.

65 I claim:

1. A razor including a base member, a double edged blade having opposite cutting edges and having a greater dimension between said cutting edges than the length of a cutting edge, said blade having a narrow central neck portion the side edges of which diverge toward the cutting edges of the blade, the blade having a communicating hole and slot in the neck portion thereof with the slot extending parallelly to the cutting edges, the base member having a seat for the blade, said seat being shaped with respect to an axis and having a small central portion at right angles to said axis, the seat having parts extending oppositely from the central portion thereof to form angles of approximately sixty degrees with said axis, guards on the base member adjacent to the opposite ends of the seat, said cover and base members being shaped in conformity with the blade, said cover member having continuous integral marginal flanges to engage the corresponding edges of the base member intermediate of the guards, the cover member having lips to press the cutting edge portions of the blade onto the seat and to flex the blade according to said seat, the cover member being in proximity to the blade whereby the blade abuts the cover member at points intermediate the lips and the central portion of the blade, means to interconnect the cover and base members including a screw, and the cover member having a plate provided with a ridge to engage in the slot of the blade, the plate being secured by the screw to said cover member.

2. A razor including a single elongated blade having its opposite cutting edges at the ends of the blade, said blade having a central opening, and a holder for the blade including a base member conforming to the shape of the blade, said base member having at its opposite ends guards for the cutting edges of the blade, said base member having a seat for the blade provided with a central substantially plane portion and opposite end portions adjacent to the guards diverging from the central portion at an angle of approximately 120 degrees between said portions, said blade seating on the central and end portions and being otherwise spaced from the base member, a cover member for flexing the blade against said seat and holding the blade thereon, said cover member being formed according to the general shape of the seat and having portions having a pressure bearing action on the central part of the blade and on the portions of the blade adjacent to the cutting edges to secure the same against said seat, and central means to connect the cover to the base through the opening in the blade.

3. A razor including a single blade having opposite cutting edges, said blade being elongated between said cutting edges an angular holder for the blade including a base and a cover between which the blade is held,

the holder having a central seat for the corresponding portion of the blade and the portions of the blade adjacent to the cutting edges thereof resting on adjacent portions of the base, the base being otherwise spaced from the blade, the cover having portions having a positive bearing action on the central portion of the blade and on the portions thereof adjacent to the cutting edges of the blade, the intermediate portions of the cover being concaved away from the base to afford spaces for receiving the blade due to flexure thereof, said intermediate portions having contact with the blade to limit the flexure thereof.

4. A razor including a base member, a double edged blade having opposite cutting edges and having a greater dimension between said cutting edges than the length of a cutting edge, said blade having a narrow central neck portion the side edges of which diverge toward the cutting edges of the blade, the blade having a communicating hole and slot in the neck portion thereof with the slot extending parallelly to the cutting edges, the base member having a seat for the blade, said seat being shaped with respect to an axis and having a small central portion at right angles to said axis, the seat having parts extending oppositely from the central portion thereof to form angles with said axis within the range of 45 to 75 degrees, guards on the base member adjacent to the opposite ends of the seat, said cover and base members being shaped in conformity with the blade, said cover member having continuous integral marginal flanges to engage the corresponding edges of the base member intermediate of the guards, the cover member having lips to press the cutting edge portions of the blade onto the seat and to flex the blade according to said seat, the cover member being in proximity to the blade whereby the blade abuts the cover member at points intermediate the lips and the central portion of the blade, means to interconnect the cover and base members including a screw, and the cover member having a plate provided with a ridge to engage in the slot of the blade, the plate being secured by the screw to said cover member.

In testimony whereof I affix my signature.
BENJAMIN GOLDMAN.
